PORABLE SIGNAL LAMP

Wayne R. Porter, Wichita, Kans., assignor to Pacific Mercury Electronics, Inc., Joplin, Mo., a corporation of California

Filed Feb. 10, 1959, Ser. No. 54,544

Term of patent 3½ years

(Cl. D72—1)

I claim:

The ornamental design for a portable signal lamp, as shown.
